UNITED STATES PATENT OFFICE.

HARRY COURTRIGHT CHEVALIER, OF MOUNT OLIVE, ILLINOIS.

DESIGN FOR A SIGN-DISPLAY CASE.

Application filed November 29, 1926. Serial No. 19,868. Term of patent 14 years.

To all whom it may concern:

Be it known that I, HARRY COURTRIGHT CHEVALIER, a citizen of the United States, residing at Mount Olive, in the county of Macoupin and State of Illinois, have invented a new, original, and ornamental Design for a Sign-Display Case, of which the following is a specification, reference being had to the accompanying drawing, forming part thereof.

The figure is a perspective view of a sign display case, showing my new design.

I claim:

The ornamental design for a sign display case, as shown.

HARRY COURTRIGHT CHEVALIER.
